Frank F. Hirsch
INVENTOR
BY Victor J. Evans
ATTORNEY

UNITED STATES PATENT OFFICE

FRANK F. HIRSCH, OF CHICAGO, ILLINOIS

REGISTER

Application filed August 20, 1928. Serial No. 300,905.

This invention relates to certain novel improvements in indicating registers, and has for its principal object the provision of an improved construction of this character which will be highly efficient in use and economical in manufacture.

Another object of my invention is to provide an indicating register which will be particularly arranged for manual operation in order that the various indicators thereon may be manually set in any desired position.

A further object of my invention is to provide a device of the above named character which will be arranged such that it may be set so as to indicate the mileage at which the oil in a motor vehicle should be changed or it may be used to indicate any other desired mileage or information required.

A still further object of the invention is to arrange a device of the above named character in such a manner that the number of changes may be recorded or so as to indicate the number of inspections made on the vehicle or the like.

A still further object of the invention is to arrange a device of the above named character such that it may be associated with the gear shifting lever of a motor vehicle in order to provide a handle therefor.

Other objects will appear hereinafter.

The invention consists in the novel combination and arrangement of parts to be hereinafter described and claimed.

The invention will be best understood by reference to the accompanying drawings, showing the preferred form of construction and in which;

Fig. 1 is a plan view of a preferred embodiment of my invention;

Fig. 2 is a view taken substantially on the line 2—2 on Fig. 1;

Fig. 3 is a view of a recording mechanism taken substantially on the line 3—3 on Fig. 1;

Fig. 4 is a sectional detail view taken substantially on the line 4—4 on Fig. 3; and

Fig. 5 is a sectional detail view taken substantially on the line 5—5 on Fig. 3.

In the drawing wherein I have illustrated the preferred form of construction for my invention 10 indicates the substantially ball

shaped housing in which my improved device is adapted to be arranged. This housing 10 includes an upper portion 11 and a lower portion 12. The lower portion 12 has provided therein a boss 13 in which a screw-threaded recess 14 is provided into which the screw-threaded end portion 15 of the gear shifting lever 16 is adapted to be fitted and a lock nut 17 is provided which is adapted to prevent displacement of the portion 12 from the lever 16.

It is apparent that portions 11 and 12 are substantially hemispherical in contour and are joined together in the present instance by providing a screw thread 18 on the inner edge of the portion 12 providing a bead 19 on the lower end of the portion 11. This bead includes a screw-threaded portion which is adapted to co-operate with the screw-threaded portion 18 so as to removably join the portions 11 and 12 together. At the upper side of the portion 11 an opening 20 is provided for a purpose to be brought forth presently.

On the interior surface of the portion 11 adjacent the end thereof extending toward the portion 12 screw-threads 21 are provided. A body member 22 is provided which includes right-angularly extending limb portions 23 and 24. The ends of these limb portions 23 and 24 are screw-threaded as indicated at 25 and are adapted for engagement with the screw threads 21. Extending upwardly from the member 22 at spaced apart points are the sleeves 26 and 27. Extended through the sleeves 26 and 27 are bolt members 28 which screw-threadedly engage recesses in the member 22. A dial member 29 is provided at the upper end of the sleeve members 26 and 27 and is supported thereby and openings are provided in this dial member 29 through which the bolt members 28 are extended and the heads of these bolt members rest in counter-sunk portions in the dial member 29 as clearly illustrated in Fig. 5. Mounted above the dial member 29 is a glass crystal 30 and when the member 22 is run inwardly the dial member 29 and the crystal 30 are moved into position below the opening 20 as clearly illustrated in Fig. 2.

Extending through the member 23 is a shaft 31. The intermediate portion of the member 23 is arranged so as to embody a portion into which the indicating drums 32 may be introduced. The indicating drums 32 are mounted for rotation about the shaft 31 as clearly illustrated in Fig. 4 and spacing washers 33 are arranged between and outside of the drums 32. In the present instance I arrange a coil spring 34 around the shaft 31 interiorly of one of the drums 32 such that it will act on one of the drums 32 and one of the washers 33 so as to place the drums under tension to resist unauthorized movement thereof. While in the present instance I show but one of these springs it is to be understood that any number might be employed without departing from the purview of my invention. On the periphery of the drums 32 I consecutively arrange numerals from 0 to 9 inclusive. In the dial 29 I provide an opening 35 which is adapted to be in alignment with the drums 32. It is apparent that since each of the drums 32 are arranged for independent movement about the shaft 31 they may be disposed such that the numerals thereon may be arranged in any desired combination as, for example, in Fig. 1 wherein I have arranged the numeral 1 on the first dial 32 so as to be disposed below the opening 35 and the remaining drums are arranged such that the numerals 4 thereon are arranged below the opening 35. It is apparent that this adjustment of the drums 32 is obtained by separating the portions 11 and 12 and manually manipulating the drums 32.

When the device is associated with a motor vehicle the drums may be arranged such that the numerals thereon below the opening 35 will indicate the mileage at which the oil in the vehicle should next be changed or they may be set so as to indicate the mileage at which tires are replaced or the device might be utilized for any other desired purpose.

It is also desirable when a device of the above mentioned character is associated with a motor vehicle to indicate the number of times the motor vehicle has been inspected or the number of times the oil has been changed as well as analogous things which might advantageously be consecutively numbered. In order to accomplish this I arranged in the arm 24 a shaft 36 on which I rotatably mount a drum 37. A spring 38 is arranged around the shaft 36 and acts on the drum 37 to tension the same in a manner substantially similar to the spring 34. Numerals are provided on the periphery of the drum 37 in a manner substantially similar to the numerals on the peripheries of the drums 32. An opening 39 is provided in the dial 29 with which the drum 37 is adapted to register and in the present instance the drum 37 is disposed such that the numer-

al 3 is arranged below the opening 39 which indicates that the third inspection or oil change has been made.

It is apparent that the exterior configuration of my device is such that it may expeditiously be substituted for the usual ball or handle provided on the gear shifting lever. It is also apparent that when the device is disposed in such a position that the settings of the various drums may be expeditiously viewed. It is also apparent that I have arranged the drums such that once they are set they will retain their position and the device is arranged such that the setting of the drums may be expeditiously accomplished. It is to be understood that if desired the portions 11 and 12 might be joined in such a manner that separation thereof will be prevented except by an authorized person.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variation and modifications as come within the scope of the appended claims.

Having thus described my invention what I claim is new and desire to protect by Letters Patent is:

1. In combination with a support, a ball having a screw threaded socket therein into which the upper end of said support may be fitted, said ball comprising separable upper and lower portions, the lower portion having said socket therein, a disc removably mounted in the upper portion, indicating members in said disc, said upper portion having an opening therein having a dial mounted therein, said dial having an opening therein through which a portion of said indicating members may be viewed.

2. In combination with a support, a ball comprising separable upper and lower sections, means for connecting said sections, the lower of said sections having an upwardly opening screw threaded socket formed therein into which the upper end of said support may be extended, the inner surface of the lower portion of the upper section of said wall being screw threaded, a disc fitted into said screw threaded portion, said disc having a substantially centrally located opening formed therein, indicating members mounted in said opening, the upper surface of said upper section having an opening therein in which a dial is mounted, said dial having an opening therein through which a portion of said indicating members may be viewed, and a crystal disposed above said dial.

3. In combination with a support, a ball comprising separable upper and lower sections, means for connecting said sections, the

lower of said sections having an upwardly opening screw threaded socket formed therein into which the upper end of said support may be extended, a lock nut for securing the connections between the lower portion of said ball and the upper end of said support, the inner surface of the lower portion of said upper section being screw threaded, a disc having the periphery thereof screw threaded whereby said disc may be removably mounted in said upper portion, said disc having an opening formed therein, a shaft extending transversely of said opening, rotatable indicating members having indicia on the peripheries thereof mounted on said shaft, the upper portion of said upper section having a dial receiving opening therein, a dial mounted in said opening having an opening therein through which a portion of the peripheries of said indicating members may be viewed.

In testimony whereof I affix my signature.
FRANK F. HIRSCH.
